Application April 1, 1953, Serial No. 346,098

6 Claims. (Cl. 235—61.6)

This invention relates generally to accumulating mechanisms for accounting machines and pertains more specifically to accumulators of the type which are operable step by step by successive electrical impulses.

The invention is designed as an improvement over the step by step operated accumulator disclosed in Patent 2,480,744, issued to Mr. C. D. Lake et al. on August 30, 1949. The patented accumulator embodies a ratchet-operated accumulator wheel actuating means which is positively reciprocated by an armature reciprocated by two magnets energized in succession. Two impulse transmitting means transmit in spaced relation groups of differentially timed electrical impulses to said magnets to effect successive unit operations of the accumulator wheel to enter the desired digit. It has been found that where a large number of these accumulators are employed in a record controlled machine, such as the type 101 IBM statistical machine, the required successive groups of impulses automatically transmitted in alternating sequence to the two magnets of each accumulator to effect the subsequent steps of operation of the accumulator wheels placed the machine under an exceedingly heavy load making it necessary to provide a rather large power supply.

Accordingly, a principal object of the invention is to provide an accumulator of the impulse controlled type which operates more simply, more economically and with less power requirements.

A further object and feature of the invention resides in the provision of means for effecting a units carry impulse through the normally closed add, subtract and reset control contacts of the accumulator along with the customary "10" contacts which are under the control of the accumulator wheel thereby eliminating the usual carry relays.

A further object of the invention pertains to the provision of a units carry means which will add an extra unit by the carry impulse to the accumulator during addition and subtraction to bring the readout to the proper digit position.

A still further object resides in the provision of means for resetting an accumulator under control of the step by step impulses of the readout during a readout cycle.

A still further object of the invention resides in the provision of means effective during a reset cycle for cutting off the last pulse to allow the accumulator wheel to reset to "9."

A further object of the invention is to provide means for preventing each accumulator ratchet wheel from turning if the related card column being sensed is void of perforations.

A further object of the invention is to provide a means for distinguishing whether a zero balance condition of an accumulator group resulted from a series of computations or whether it resulted from the fact that no entries were made.

Other objects of the invention will be pointed out in the following description and claims and illustrated in

the accompanying drawings, which disclose, by way of example, the principle of the invention and the best mode, which has been contemplated, of applying that principle.

In the drawings:

Fig. 1 is a view in side elevation of an assembled accumulating unit constructed according to the present invention.

Fig. 1 is a view in side elevation of an assembled accumulating unit constructed according to the present invention.

Fig. 2 is an end view taken on the line 2—2 of Fig. 1.

Fig. 3 is a transverse sectional view taken on the line 3—3 of Fig. 1.

Fig. 4 is a longitudinal sectional view taken on the line 4—4 of Fig. 3, showing the details of the digit readout unit.

Fig. 5 is a perspective view showing the contact assemblies associated with each accumulator wheel.

Fig. 6 is a timing chart.

Figs. 7a and 7b taken together form a wiring diagram showing the electrical wiring connections of the instrumentalities employed for two orders of the accumulator constructed according to the present invention.

The parts and mechanism forming each of the accumulator units are carried by a support plate which is mounted in a vertical plane in the machine. As is well known, to form a multidenominational amount receiving accumulator a plurality of such units are mounted side by side and electrically interconnected in a manner to be described so that units carries or transfers may be effected from each lower order accumulator wheel to the next higher order wheel. Carried by the plate 20 (Fig. 1) is an "add" magnet 21 having an armature 22 which is pivoted at 23 to a yoke member 24. The right-hand end of the armature 22 has attached thereto a stud 25 on which is pivotally mounted an upstanding lever 26. Pivoted on a stud 27 carried by the lever 26 is an operating pawl 28 and said pawl is urged by a spring 29 which is extended from a tail of the pawl 28 to a support plate 30, into engagement with a tooth 31 of a ratchet wheel 32. The support plate 30 is mounted on an internally threaded stud 33 on the plate 20 by means of a slot 34 and screw 35, said slot 34 and screw 35 affording a means for adjusting the tension of the spring 29.

It is evident that when the armature 22 is attracted by the core of the energized "add" magnet 21 it will rock the lever 26 clockwise about its pivotal stud 36 and pawl 28 will be moved to the right under the now idle ratchet wheel 32 to engage the next tooth to the right thereof. In such position the pawl 28 is in a position to rotate the ratchet wheel 32 clockwise one ratchet tooth when the magnet 21 is de-energized. When the magnet 21 is de-energized the tension of spring 29 is sufficient to positively rock the lever 26 counterclockwise to effect the one-tooth rotation of ratchet wheel 32. In this manner a unit is entered for each reciprocation of lever 26.

The accumulator wheel assembly for each order consists of an "add" ratchet wheel 32, a ratchet wheel 37 which is associated with a retrograde preventing mechanism to be described and which is also used to latch a contact in closed position when the first unit is entered, and two control cams 38 and 39 associated with the units carry mechanism.

By any suitable means the two ratchet wheels 32, 37 and the two cams 38, 39 are fastened to spacer discs 40 (Fig. 3) and they, in turn, are attached by any suitable means to a shaft 41. From Fig. 3 it will be seen that a reduced end 42 of the shaft 41 is journaled in a bracket 43 which is carried by the plate 20. The other end of shaft 41 has a reduced portion 44 and is journaled in the plate 20.

The retrograde preventing mechanism consists of a

lever 45 (Fig. 1) which is pivoted upon the stud 36, said lever 45 being normally urged in a counterclockwise direction about stud 36 by means of a spring 46 mounted within a slotted block member 47 carried by the plate 20. The lever 45 has a hook shaped portion which engages the teeth 48 of the ratchet wheel 37 and it will be evident that during unit entries to the magnet 21 the lever 45 will be cammed clockwise by the teeth 48 on ratchet wheel 37. At the end of each one-tooth movement of the ratchet wheel 37 the spring 46 will pivot lever 45 counterclockwise and the hook shaped portion of said lever will engage a tooth 48 on the ratchet wheel 37 to prevent retrograde or counterclockwise movement of the ratchet wheel and cam assembly.

Additive entry operations

Any suitable type of digit entry control means may be provided to impulse the magnet 21 so that by successive steps of operation of each accumulator wheel the desired digit will be additively entered therein. As illustrative of one form of entering control mechanism the present embodiment includes means for effecting additive entries under control of a perforated record 49 shown in Fig. 7a. The record analyzing means is shown diagrammatically since it is well known in record controlled accounting machines. As is well known, a differential location of a perforation determines the digital value. For the illustrative form of a card a perforation near the front edge of the card may represent a special 0 position punching, a perforation at the 5 position represents 5 in the units order and a perforation at the 9 position represents 9 in the highest order. The entering means will best be understood by reference to the wiring diagram of Figs. 7a and 7b, it being noted that for purposes of simplicity only two denominational orders are shown but obviously the capacity may be increased according to entry requirements. As a further illustration of the embodiment of the present invention the accumulator orders may be considered to be a part of the well-known IBM reproducing punch disclosed in Patent Re. 21,133 and the brushes 50 (Fig. 7a) may be considered to be the same as the read brushes 15 shown in Figs. 3 and 10b of said patent. Also the punch magnets PM1 and PM2 (Fig. 7a) may be considered the same as the punch magnets PM shown in Fig. 10b of said patent.

For conditioning the machine for addition under control of a series of cards 49 which, as is well known, automatically and sequentially pass through the record analyzing means, those cards which are to be added may have a perforation set aside in a particular column of the card which is used to effect energization of a plus control relay which in turn conditions the accumulator to add. The circuit for energizing the plus control relay extends from line 51 (Fig. 7a), wire 52, cam contact C9, CL card lever contacts (which, as is well known, are physically closed by the cards as they pass through the machine), common contact roll 53, brush 50 for the column having the 0 perforation, plug connection 54, the pick coil plus control relay R457 and line 55. Relay R457 holds up through a circuit which extends from line 51, wire 56, cam C27, contacts R457-1 now closed, the hold coil of relay R457 and line 55. Accordingly, the R457-3 and R457-4 contacts (Fig. 7b) remain transferred throughout the sensing of the digits 0 through 9 to condition the accumulator orders for adding. It is to be understood that the plus control relays need not be controlled by a signal from the card. They may be controlled, for example, from a machine cycle impulse when it is desired to add all of the cards.

Referring to Fig. 7b it will be seen that there are two cam contacts C29 and C30 connected in parallel. These cam contacts provide the add impulses to all of the add magnets of the accumulator units and they are timed to emit nine short impulses, the first between "0" and

"1" time and the last between "8" and "9" time on the machine index as shown in Fig. 6.

With the plus control relay R457 energized, as previously described, a circuit is completed from line 51 (Fig. 7b), wire 57, cam contacts C29 and C30, the normally closed side of contacts R463-2, contacts R457-4 now transferred, normally closed side of contacts R458-4, normally closed side of contacts R450-7, the add magnet 21 in the units order and line 55. The units order "add" magnet 21 then will be impaled once for each digit position on the record card until the read brushes 50 sense a hole and for each impulse the related ratchet wheel 32 will move clockwise one tooth position as previously described. A similar circuit is completed 15 to the "add" magnets of all the accumulator units being used to start their accumulator wheels turning.

It should be mentioned at this point that all of the accumulators are reset to 9, by circuits to be later described, at the end of an opening cycle and consequently the first 20 impulse to the "add" magnet will move the accumulating wheel from 9 to 0. This will be understood by referring to Fig. 4, which is a view looking at the back of an accumulator unit plate 20 and showing a well known type of accumulator digit readout unit. When an accumulator 25 is reset to 9 a wiper 58 will be in contact with a contact strip 59 corresponding to position 9 and a wiper 60 will be in contact with a common conducting segment 61. When the first impulse is received by the "add" magnet 21 the accumulator wheel will turn one tooth 30 and now wiper 58 will be in contact with the common conducting segment 61 and wiper 60 will be in contact with the contact strip 59 corresponding to 0 indicating that the accumulator has moved from 9 to 0. The readout unit will be described more in detail later in connection with the readout circuits. The movement of the 35 accumulator wheel from 9 to 0 is significant at this point because the normal carry circuit that takes place is utilized to bring the accumulator wheel to the correct digit position during adding and subtracting cycles.

40 Referring to Fig. 7a it may be seen that the card is fed past the sensing brushes 50 with the 12 edge first. Assuming, for example, that the five hole on the card is to be added the "add" magnet 21 for the units position 45 accumulator will receive five impulses from cams C29 and C30 (between 0 and 5 time on the machine index) until the five hole is sensed. When the five hole is sensed 50 a circuit is completed from line 51 (Fig. 7a), wire 52, cam contact C9, CL card lever contacts, common contact roll 53, brush 50 for the column having the 5 perforation, a plug wire connection 62 to the entry hub for the units position accumulator (Fig. 7b), normally closed contacts R453-4, the second pick coil of count control relay R463 and line 55. The hold circuit for relay R463 extends from line 51, wire 63, cam contacts C31, 55 wire 64, contacts R463-1 now closed, the hold coil of relay R463 and line 55. The energization of count control relay R463 transfers contacts R463-2 in the circuit to the "add" magnet in the units position and as a result the accumulator wheel stops after having received five 60 pulses from C29 and C30.

65 Looking at Fig. 4 it will be seen that with the accumulator reset to 9 five impulses to the "add" magnet 21 will position the wiper 60 on contact strip 59 corresponding to the 4 position and as such the accumulator would read out a 4 instead of the 5 that was sensed. The added impulse required to bring the accumulator readout to the 5 position is effected when the accumulator wheel passes from 9 to 0. As is well known, carry circuits are effected between accumulator orders by the mechanical closure 70 of a "10" contact as each accumulator wheel passes from 9 to 0. The mechanism for closing the "10" contacts will be described in detail later and it will suffice for now to say that closure of the "10" contact for the units position accumulator will complete a circuit at carry time from 75 line 51 (Fig. 7b), wire 65, cam contact C28, the "10"

contact in the units position now closed, the normally closed side of contacts R457-3, normally closed side of contacts R458-3, normally closed side of contacts R450-6, the "add" magnet 21 in the tens position and line 55. Since the tens position accumulator was reset to 9 the carry impulse will cause the tens accumulator wheel to pass from 9 to 0. However, before the carry impulse terminates and the tens accumulator wheel actually moves, the carry impulse is also directed from the "10" contact in the units position, through the closed "9" contacts in the tens order, the normally closed side of contacts R450-3, the carry exit hub (since only a two position accumulator unit is shown), plug wire connection 66 to the carry entry hub, normally closed contacts R450-5, normally closed side of contacts R457-4, normally closed side of contacts R458-4, the normally closed side of contacts R450-7, "add" magnet 21 in the units position and line 55. It is evident that with the above-described carry impulse the units position accumulator into which the sensed five perforation was entered will actually receive six impulses, and as a result its related wiper 60 will be positioned on the contact strip 59 corresponding to the 5 position indicating that a 5 has been added into the accumulator. Addition is similarly accomplished in all of the accumulator positions.

Subtraction entries

The machine may also be conditioned to effect subtraction of amounts represented by a series of cards. Subtracting operations are performed by the complementary process, that is to say, a digit is entered in each order which is the 9's complement of the represented digit. For example, to enter 95 subtractively the number 99904 would be entered in the accumulator. A nine will be entered for all zeros in a number.

The machine is conditioned for subtracting operations by energizing a minus control relay R458 (Fig. 7a) from a perforation in the card in the same manner that plus control relay R457 was energized for adding operations. Relay R458 will hold up through the reading portion of the machine cycle by a circuit which extends from line 51, wire 56, cam contact 27, contacts R458-1 now closed, the hold coil of relay R458 and line 55.

Referring to the units position accumulator it may be seen that contacts R458-4 now transfer to signal a subtraction operation but the circuit to the "add" magnet 21 will remain open until count control relay R463 is energized to transfer contacts R463-2. As was described in connection with addition, relay R463 will be energized when the sensing brushes sense a hole in the card. Using the 5 perforation again, at "5" time in the machine cycle sensing brush 50 will complete the circuit to energize the second pick coil of relay R463 and a circuit will be completed from line 51, wire 57, cam contacts C29 and C30, contacts R463-2 now transferred, contacts R458-4 now transferred, the normally closed side of contacts R450-7, the "add" magnet 21 in the units position and line 55. Referring to Fig. 6 it can be seen that cam contacts C29 and C30 will transmit four impulses to the magnet 21 between "5" and "9" time on the machine index and accordingly the units accumulator wheel would be positioned with wiper 60 in contact with contact strip 59 corresponding to position 3. However, as was previously described, the usual carry impulse will add one more pulse to magnet 21 between "9" and "0" time and consequently the accumulator wheel will actually be positioned at 4 which is the complement of the five hole sensed. Subtraction on a 9's complement basis is similarly carried out in all of the accumulator positions.

Units carry means

The units carry means provides for the entry of a unit to an accumulator wheel when the next lower order wheel passes from 9 to 0. The carry means consists of elec-

trical circuits which have already been described and hence only the mechanical structure necessary to effect a carry operation, which in itself is well known, will be generally explained.

Referring to Fig. 5, cam 39 has two cam projections 67 which are alternately effective at each half revolution of the accumulator wheel when it passes from 9 to 0 to rock a double arm 68, pivoted on a support rod 69, counterclockwise. The left end of the arm 68 carries a block 70 of insulating material which normally overlies a spring blade of contacts which make up the customary "10" contacts. Counterclockwise movement of the arm 68 will close the "10" contacts and said arm 68 will be latched in rocked position by having the right terminal end of the arm 68 engaged by a latching notch 71 of a spring operated latching bell crank 72 which is loosely pivoted upon a rod 73. The bell crank 72 will hold the "10" contacts closed until after carry time at which time a circuit is provided to energize a magnet 74 which attracts its armature 75 and the latter, by cooperation with a tail 76 of the latching arm 72, will rock the same counterclockwise to unlatch the arm 68. This circuit extends from line 51 (Fig. 7b), wire 77, cam contacts C32, latch magnets 74 for all accumulator positions and line 55.

One feature of the present invention is the manner in which the carry circuits have been simplified. Recalling to mind the carry circuits previously described in connection with the adding operations it will be noted that carry is affected by a single add impulse which will test all of the accumulator "10" contacts every cycle, each transferred contact completing the circuit to the next high order accumulator add magnet, adding one. Such an arrangement eliminates the existing practice of energizing carry relays to transfer a group of related contacts so as to prepare the carry circuits for unit carry operations upon the closure of the "10" contacts.

Provision is also made, as is customary, to concurrently effect a carry to a still higher order if this order stands at 9 and a units carry causes the next lower order wheel to pass from 9-0. This is performed under control of the customary "9" contacts. Referring to Fig. 5 cam 38 has two recesses 78 which are alternately effective at each half revolution of the accumulator wheel when it represents 9 to allow an arm 79 loosely pivoted on the support rod 69 to rock counterclockwise. Upon such movement a block 80 of insulating material, attached to the end of the arm 79 and overlying a spring blade of contacts which make up the "9" contacts, is lowered to close same. Referring to Fig. 7b it can be seen that if the 9's contact is closed in the tens order the impulse circuit through the "10" contacts in the units order, which was previously traced, is immediately extended through the "9" contacts in the tens order, and the normally closed side of contacts R450-3, and thence to the carry exit hub. Thus, it is not necessary to wait until the "10" contacts in the tens order are closed to effect a carry and carries in a plurality of orders are concurrently effected under such circumstances.

Total readout means

In order to secure the representation of the digits of a total standing on each accumulator wheel each accumulator unit has associated therewith a commutator type of readout unit shown in Fig. 4. The readout unit is of a well-known construction and consists of a plate of insulating material 81 which is secured by any suitable means to the support plate 20 as is, therefore, stationary with respect to the rotatable wiper structure 82. This wiper structure fits over a flattened portion 83 of the right-hand end of shaft 41 and is secured thereto by a screw 84. The wiper structure, as previously mentioned, consists of the wipers 58 and 60, one of which makes contact with the common conducting segment 61 as the other wiper makes contact with digit representing contact points which are carried by plate 81.

There is a diagrammatic showing of the readout in Fig. 7b and associated electrical connections. Emitter EM shown in Fig. 7b transmits a series of differentially timed impulses (see Fig. 6) to the digit representing contact points to thereby transmit differentially timed digit representing impulses selected according to the contact point 59 contacted by a wiper, to punch magnets PM1 and PM2. A plurality of punch magnets is provided, one for each denominational order, and each is energized by a differentially timed digit representing impulse when the machine is signalled to take a readout cycle. For punching a total standing on the accumulator, a punching mechanism may be provided such as is shown in the patent to C. D. Lake, No. Re. 21,133. This type of punching mechanism is well known and, therefore, is not shown herein.

A total readout cycle is initiated by plug wiring from an all cycles impulse hub (Fig. 7a) to a readout hub to energize a readout control relay R453. The circuit extends from line 51, wire 85, cam contact C21 which closes to transmit a control impulse once each cycle as shown in Fig. 6, all cycles impulse hub, plug connection 86, readout hub, the pick coil of relay R453 and line 55. Relay R453 holds throughout the readout cycle by a circuit which extends from line 51, wire 87, cam contact C22, contacts R453-1 now closed, the hold coil of relay R453 and line 55.

With the example "5" added into the units position accumulator at 5 time in the cycle a circuit will be initiated from line 51 (Fig. 7b), wire 88, emitter EM "5" spot, normally closed side of contacts R459-8, contact 59 corresponding to position 5 on the accumulator readout commutator, wiper assembly 82 in the 5 position, common strip 61, wire 89, normally closed contacts R463-3, readout control contacts R453-3 now closed to the exit hub for the units position accumulator. The counter exit hub is plug connected to one of the punch direct hubs (Fig. 7a) to complete the circuit through a punch magnet PM1 or PM2 and line 55 resulting in the punching of a 5.

A subtracted entry is read out in a similar manner through an inversion relay which is energized when a negative balance test impulse finds a "9" in the high order counter position. The test impulse circuit is conditioned between "9.5" and "11.6" time of every cycle by the energization of relay R74 (Fig. 7b) through a circuit which extends from line 51, wire 90, cam contact C15, the pick coil of relay R74 and line 55. Assuming, then, that the tens position accumulator stands at 9 indicating a subtraction entry was made in the two position accumulator group shown, a circuit will be initiated at "11" time of the cycle which extends from line 51 (Fig. 7b), wire 88, the 11 spot of emitter EM, contacts R74-1 now transferred, the 9 contact segment of the tens position accumulator, wiper assembly 82, common segment 61, wire 91, contacts R74-2 now closed, and the negative balance test exit hub. The negative balance test exit hub is plug connected to the negative balance control hub (Fig. 7a) to complete the above circuit to the pick coil of inversion relay R459 and line 55. The hold circuit for relay R459 extends from line 51, wire 87, cam contact C22, contacts R459-1 now closed, the hold coil of relay R459 and line 55. Referring to Fig. 7b it can be seen that with the contacts R459-3 through R459-12 transferred that the digit read out of the accumulator will be the 9's complement of the digit that was entered into the accumulator. For example, a 7 in the accumulator will read out as a 2. This is a well-known practice with respect to reading out subtractive entries and further discussion of same is not believed to be necessary.

The negative balance test impulse at "11" time is also directed from the R74-2 contacts, through the normally closed R456-3 contacts to a negative balance punch hub. The negative balance punch hub is generally plug connected to a punch direct hub (Fig. 7a) to effect the

punching of an "X" designation in all negative balance cards.

The R456-3 contacts are used to prevent the negative balance test impulse from reaching the negative balance punch hub whenever the accumulator group fails to receive an entry. This feature provides a useful means for distinguishing between a zero balance condition caused by non-entry into the accumulator group due to inactive cards and a zero balance resulting from a series of computations from active cards such as adding a series of amounts and then subtracting a series of amounts the sum of which equals the sum of the amounts added. In the case of non-entry the accumulator never leaves its reset position of 9. In the case of entry with zero balance the accumulator returns to its reset position of 9. In either case, then, the highest order position of the accumulator group will be standing at 9 and consequently will emit the negative balance test impulse.

To carry out this function a negative balance "X" punch suppression relay R456 is provided. This relay is energized whenever reset relay R450 becomes energized by a circuit which extends from line 51 (Fig. 7a), wire 87, cam contact C22, contacts R450-1, the pick coil of relay R456 and line 55. Relay R456 holds through a circuit which extends from line 51 (Fig. 7a), wire 101, the normally closed minus control relay contacts R458-2, normally closed plus control relay contacts R457-2, contacts R456-1 now closed, the hold coil of relay R456 and line 55. It is evident that if neither plus control relay R457 nor minus control relay R458 is energized to effect an entry into the accumulator group, the hold circuit for relay R456 will be completed and contacts R456-3 will remain open to prevent the punching of an "X." Upon an entry into the accumulator group either contacts R457-2 or contacts R458-2 will be open to prevent relay R456 from holding up and the R456-3 contacts will close to complete the "X" punching circuit.

Punched card groups may be run through the read feed of the well-known reproducing punch disclosed in Patent Re. 21,133 and entries made into accumulator groups. A summary card may be fed through the punch feed for each group of cards in the read feed in which will be punched a summary of the information accumulated from its related card group. On a zero balance condition each summary card will be punched with zeros and only those summary cards which are controlled from an accumulator group, which is at zero balance as a result of a series of computations, will be "X" punched.

Resetting of the accumulator

The resetting of an accumulator having an additive entry therein takes place during the readout cycle and is brought about by plug connecting an all cycles impulse hub (Fig. 7a) to a reset hub to complete a circuit through the normally closed side of contacts R459-2, normally closed side of contacts R455-2, the pick coil of reset relay R450 and line 55. The hold circuit for relay R450 extends from line 51, wire 87, cam contact C22, contacts R450-1 now closed, the hold coil of relay R455 and line 55.

Referring to the units position accumulator it can be seen that the readout circuit previously traced to emit a 5 impulse from the exit hub will, when the accumulator is signaled to reset, also extend through the normally closed R56-2 contacts, contacts R450-7 now transferred, "add" magnet 21 and line 55.

Referring once again to Fig. 5 there is seen a third arm 93 pivoted on the support rod 69 and having a block 94 of insulating material which normally overlies a spring blade of contacts which make up what is hereinafter called the "A" contacts. The arm 93 is rocked by the teeth on the accumulator ratchet wheel 37 and when the latch magnet 74 is energized after carry time each cycle, as previously described, a latching bell

crank 95 loose on the rod 73 will disengage the right terminal end of arm 93 allowing said arm 93 to rock clockwise thereby opening the "A" contacts. The "A" contacts will remain open until the reset circuit above described transmits an impulse to the accumulator "add" magnet. As the accumulator ratchet wheel 37 moves as a result of this impulse the arm 94 will be rocked counterclockwise closing the "A" contacts. The bell crank arm 95 will hold the "A" contacts closed until the latch magnet 74 receives another impulse.

With the closure of the "A" contacts a circuit is completed from line 51 (Fig. 7b), wire 63, cam contact 31, wire 96, contacts R450-2 now closed, the "A" contacts for the units position accumulator now closed, the first pick coil of count control relay R463 and line 55. Relay R463 holds through the R463-1 contacts and cam contact 31 as previously described. Energization of relay R463 causes the R463-3 contacts to open thus interrupting the circuit to the units position accumulator exit hub. As a result the remaining impulses from the emitter EM which cause the accumulator to step to the reset position are eliminated from the readout circuit.

At "8.5" time on the machine index after the "8" pulse from emitter EM has caused the accumulator to step to the "9" position a circuit is completed from line 51 (Fig. 7a), wire 97, cam contact C18, the pick coil of relay R56 and line 55. The R56-2 contacts in the reset circuit now open to filter out the emitter "9" impulse thus leaving the accumulator reset to "9" instead of the customary "0." In effect, then, the accumulator is reset in a unique manner by utilizing the step by step impulses of the readout circuit to reset the ratchet wheel with means for cutting off the last pulse to allow the wheel to stop at "9" and this is considered to be one of the novel features of the present accumulator.

In the case of a negative balance the reset operation is delayed one cycle to allow the accumulator to read out through the inversion relay. This is accomplished by inversion relay contacts R459-2 in the reset entry hub circuit. On a negative balance, then, contacts R459-2 transfer and instead of picking the reset relay R450 the pick coil of reset delay relay R455 is energized. Relay R455 holds through a circuit which extends from line 51, wire 98, cam contact C25, contacts R455-1 now closed, the hold coil of relay R455 and line 55. The delay relay contacts R455-2 will transfer and remain transferred from 0.1 time of the delay cycle until 11.1 time of the following cycle. At 12.0 time in the following cycle a circuit is completed from line 51, wire 99, cam contact C26, contacts R455-2 transferred, the pick coil of reset relay R450 and line 55 thus initiating a reset cycle to reset the accumulator in the manner previously described.

Upon completion of a reset cycle, a reset test impulse checks the operation through the "9" contacts of each reset accumulator group. For example, the two accumulators of the particular group shown have been correctly reset, a circuit will be completed from line 51 (Fig. 7b), wire 65, cam contact C8, contacts R450-3 still transferred, the "9" contacts on the tens position accumulator, the "9" contacts on the units position accumulator, contacts R450-4 still closed, the pick coil of reset test relay R448 and line 55. Relay R448 will hold through a circuit which extends from line 51 (Fig. 7a), wire 100, cam contact C16, contacts R448-1 now closed, the hold coil of relay R448 and line 55. The energization of relay R448 will allow the machine operations to continue whereas failure to energize relay R448 will start a chain reaction of interlocks (which form no part of the present invention and therefore are not shown) to stop all machine functions.

It is pointed out that each accumulator group will have its own related reset relay and reset test relay as in the case of the two position group shown and described

herein. With such an arrangement it is possible to test any accumulator group that has been signaled to reset. Also, if an accumulator group is found to have failed to reset correctly, that accumulator group may be subsequently reset without disturbing any of the other accumulator groups.

Means are provided with this type of accumulator for taking care of the situation where the card field being accumulated is not completely punched. If the five used in the previous addition example was sensed from the units column of a two column field and the remainder of the field was blank (no zero punches) the tens position accumulator would be allowed to make a complete revolution returning to "9" because its related count control relay received no impulse. To prevent this unnecessary movement a "0" hub is provided connected to the "0" contact segment of the emitter EM. The "0" hub may be plug connected to the tens position accumulator entry hub. As a result a "0" impulse will be transmitted to the count control relay R462 and the tens position accumulator wheel will not move since the C28 and C29 impulse circuit to the "add" magnet is opened by the R462-2 contacts before the first impulse is transmitted. As many "0" hubs may be provided as are required to take care of all blank column accumulator positions.

If the "0" impulse circuit, just described, is wired to accumulator positions to prevent the accumulator wheels from unnecessarily turning provisions must be made to filter out the "0" impulse during readout cycles so that readout may take place. Referring to the tens position accumulator, for example, when reset relay R453 is energized to initiate a readout cycle, the R453-2 contacts open to prevent the "0" impulse, or a machine, brush or counter impulse for that matter, from energizing the second pick coil of relay R462. As a result the R462-3 contacts in the readout circuit for the tens position accumulator will be normally closed to allow readout to take place.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a cyclically operable accumulating mechanism of the step by step type wherein a digit entry in digit receiving means of each order is initiated by a succession of impulses to a magnet, said digit entry being completed in a particular order when means under control of a digit representing impulse becomes effective to interrupt the succession of pulses to the magnet for that order, the combination of normally ineffective impulse transmitting means for transmitting successive impulses to said magnet, means for selectively rendering said impulse transmitting means operable, actuating means under control of said magnet for moving the digit receiving means to a digit representing position at the termination of each impulse to said magnet, normally closed add, subtract and reset control contacts associated with each order, a pair of 10 contacts under control of the digit receiving means of lower order and adapted to be closed thereby when a certain digit position is represented, cyclically operable means for emitting a single add impulse, and means dependent upon only the closure of said 10 contacts in a lower order for transmitting said add impulse through said control contacts to the corresponding magnet of the next higher order to enter a unit carry.

2. In a cyclically operable accumulating mechanism of the step by step type wherein a digit entry in digit receiving means of each order is initiated by a succession

11

of impulses to a magnet, said digit entry being completed in a particular order when means under control of a digit representing impulse becomes effective to interrupt the succession of pulses to the magnet for that order, the combination of normally ineffective impulse transmitting means for transmitting successive impulses to said magnet, means for selectively rendering said impulse transmitting means operable, actuating means under control of said magnet for moving the digit receiving means to a digit representing position at the termination of each impulse to said magnet, cyclically operable means for emitting a single add impulse, means under control of the digit receiving means of lower order when a certain digit is represented for transmitting said add impulse during adding and subtracting cycles to the magnets of all higher orders, and means under control of the highest order for transmitting said add impulse to the magnet of said lower order causing the digit receiving means in said lower order to move to the next digit representing position.

3. In a cyclically operable accumulating mechanism of the step by step type wherein a digit entry in digit receiving means of each order is initiated by a succession of impulses to a magnet, said digit entry being completed in a particular order when means under control of a digit representing impulse becomes effective to interrupt the succession of pulses to the magnet for that order, the combination of normally ineffective impulse transmitting means for transmitting successive impulses to said magnet, means for selectively rendering said impulse transmitting means operable, actuating means under control of said magnet for moving the digit receiving means to a digit representing position at the termination of each impulse to said magnet, readout means associated with said digit receiving means and movable therewith to represent the digit entered in said digit receiving means, cyclically operable means for transmitting digit representing impulses in succession to said readout means, means for selectively rendering said digit representing impulse transmitting means and said readout means effective to read out the digit entered in said digit receiving means, means for concurrently initiating a reset operation whereby said cyclically operable means will also transmit digit representing impulses to said digit receiving means, and means under control of said digit receiving means when the first reset impulse is received for preventing the remaining digit representing impulses from reading out of said readout means.

4. In a cyclically operable accumulating mechanism of the step by step type wherein a digit entry in digit receiving means of each order is initiated by a succession of impulses to a magnet, said digit entry being completed in a particular order when means under control of a digit representing impulse becomes effective to interrupt the succession of pulses to the magnet for that order, the combination of normally ineffective impulse transmitting means for transmitting successive impulses to said magnet, means for selectively rendering said impulse transmitting means operable, actuating means under control of said magnet for moving the digit receiving means to

12

a digit representing position at the termination of each impulse to said magnet, cyclically operable means for transmitting digit representing impulses, means for selectively rendering said cyclically operable means effective after completion of digit entry to transmit the digit representing impulses to said digit receiving means to reset same, and cyclically operable means for preventing the last digit representing impulse from entering said digit receiving means.

5. In a cyclically operable accumulating mechanism of the step by step type wherein a digit entry in digit receiving means of each order is initiated by a succession of impulses to a magnet, said digit entry being completed in a particular order when control means operated by a digit representing impulse becomes effective to interrupt the succession of pulses to the magnet for that order, the combination of normally ineffective impulse transmitting means for transmitting successive impulses to said magnet, means for selectively rendering said impulse transmitting means operable, actuating means under control of said magnet for moving the digit receiving means to a digit representing position at the termination of each impulse to said magnet, cyclically operable means for transmitting digit representing impulses, normally ineffective means for transmitting a predetermined digit representative impulse from said cyclically operable means, and means for selectively rendering said last named means effective to operate said control means to prevent the entry receiving means from receiving impulses from said first impulse transmitting means.

6. In a cyclically operable accumulating mechanism of the step by step type wherein a digit entry in digit receiving means of each order is initiated by a succession of impulses to a magnet, said digit entry being completed in a particular order when means under control of a digit representing impulse becomes effective to interrupt the succession of pulses to the magnet for that order, the combination of normally ineffective impulse transmitting means for transmitting successive impulses to said magnet, entry control means selectively operable to render said impulse transmitting means operable, actuating means under control of said magnet for moving the digit receiving means to a digit representing position at the termination of each impulse to said magnet, an output control hub associated with said accumulating mechanism, cyclically operable means for emitting a timed impulse, and means under control of said entry control means and effective upon operation of the latter to transmit said timed impulse to said control hub when the digit receiving means in the highest order stands at 9, said means being effective to prevent the transmission of said timed impulse to said control hub if said entry control means is not operated.
